UNITED STATES PATENT OFFICE

HENRY W. PLEISTER, OF WESTFIELD, AND JOHN KARITZKY, OF GARWOOD, NEW JERSEY, ASSIGNEES, BY DIRECT AND MESNE ASSIGNMENTS, TO HENRY B. NEW-HALL CORPORATION, OF GARWOOD, NEW JERSEY, A CORPORATION OF NEW JERSEY

NAIL EXPANSION

Application filed August 20, 1926. Serial No. 120,390.

Our invention relates to expansion bolts, and more particularly to a nail expansion shield formed of wire or similar material, the wire being either round, flat, or any other form.

Our invention further relates to a wire shield, the cross-section of which is less than a complete circle, to permit an expanding member to engage with the shield and also with the walls of the hole in which the shield is mounted.

Our invention further relates to a wire shield formed of a plurality of disconnected wire units.

15 Our invention further relates to an expansion shield formed of a primary and a secondary unit, the units being nested parallel to each other.

Our invention further relates to certain 20 articles of manufacture and combination which will be more fully hereinafter described and pointed out in the claims.

In the accompanying drawings the same 25 reference numerals refer to similar parts in the several figures.

Fig. 1 is a perspective view of a wire unit;

Fig. 2 is a side elevation of the primary unit shown in Fig. 1;

Fig. 3 is a plan view of the primary unit 30 shown in Fig. 2;

Fig. 4 is a perspective view of the secondary unit to be nested with the primary unit, Fig. 1;

Fig. 5 is a side elevation of the complete 35 wire shield formed of the primary and secondary units nested;

Fig. 6 is a front elevation taken 90° from the position shown in Fig. 5;

Fig. 7 is a horizontal section on the line 40 16—16 of Fig. 6;

Fig. 8 is a vertical section showing the expanding member being inserted into the wire shield;

Fig. 9 is a horizontal section.

45 In our invention the wire shield is formed of a primary unit 18 and a secondary unit 19. The primary unit is shown detached in Figs. 1 to 3 and is formed from a length of commercial soft wire of any suitable contour bent to form the head member 20 and

the longitudinally extending strands 21 and 22. The strand 21 is bent back on itself to form the longitudinally extending strand 23, the end of that strand being bent below the level of the loop head member 20 to form 55 the head member 24. The strand 22 is bent back on itself to form the longitudinally extending strand 25, the end of this strand being bent below the level of the loop head member 20 to form the head member 26. 60

The secondary unit 19 (Fig. 4) is formed from a similar length of commercial soft wire to form the outwardly extending loop head member 27 and the longitudinally extending strands 28 and 29. The end of the strand 28 is bent back sharply upon itself to form the strand 30 which is preferably not as long as the strand 28. In the same manner the end of the strand 29 is bent back upon itself 65 to form a short strand 31.

The two units 18 and 19 are nested and brought into cooperation with each other by bringing the loops 32, 32 of the secondary unit 19 in line with the openings 33, 33 between the different strands 21, 23 and 22 and 70 25 of the primary unit. The interval 34 (Fig. 4) between the loops 32, 32 of the secondary unit is just sufficient to straddle the strands 21 and 23 and 22 and 25 of the primary unit and to exert a slight pressure tending to force the strands 21, 23 and strands 22 and 25 towards each other with a yielding pressure, the longitudinally extending strands of the secondary unit 19 riding on the exterior surface of the strands of the first 75 unit, as shown more clearly in Figs. 6 and 7.

By having the head members 24 and 26 of the primary unit 18 below the head member 20 of that unit permits the head member 27 of the secondary unit to be brought to rest 80 on the head members 24 and 26 of the primary unit and be substantially flush with the head member 20 of that unit, as shown in Fig. 5.

The different units 18 and 19 may, if desired, be separately positioned in the hole 9 85 of the support 10 so as to hold the work 12 to the surface 40 of the support. Preferably, however, the different units will be nested as shown in Fig. 5, which would be their assembled and commercial shipping position. 90

When the expanding member, as for example, the nail 13 is driven into the complete wire shield formed of the two units 18 and 19, the different longitudinally extending strands of each of the units will be forced 5 radially by the nail and make a firm hold or bond with the surface 14 of the hole.

While we have shown a smooth nail, it is to be understood that the nail may be provided, 10 with a roughened surface, and that a threaded bolt provided with square or countersunk head may be employed instead of a nail. It will be noted that my expansion shield may be made at minimum cost, that it is simple and 15 will give the maximum efficiency for a given size shield. It is further to be noted that the different wire shields, or wire units, are each open constructions, which will freely allow galvanizing by the hot process.

20 Having thus described this invention in connection with illustrative embodiments thereof, to the details of which we do not desire to be limited, what is claimed as new and what is desired to secure by Letters Patent is 25 set forth in the appended claims.

What we claim is:

1. A new article of manufacture comprising a wire expansion shield formed of a primary wire unit having a plurality of longitudinally extending strands of wire separated from each other, and a secondary wire unit adapted to be nested on the exterior of the strands of the primary unit and parallel to 30 said strands.

35 2. A new article of manufacture comprising a wire expansion shield formed of a primary resilient wire unit having a plurality of longitudinally extending strands of wire separated from each other, and a secondary 40 resilient wire unit having a plurality of longitudinally extending strands of wire adapted to be nested on the exterior of the strands of the primary unit and force the strands of that unit towards each other to yieldingly 45 hold the two wire units together.

50 3. A new article of manufacture comprising a wire expansion shield formed of a primary wire unit and a secondary wire unit, head members on the primary unit, one head member being lower than the other head member, and a head member on the secondary unit adapted to rest on the lower head member of the primary unit.

55 4. A new article of manufacture comprising a wire expansion shield formed of a primary wire unit having a plurality of longitudinally extending strands, and a secondary wire unit unattached to the first unit engaging and cooperating with the exterior surfaces of the longitudinally extending strands 60 of the first unit and held thereon by spring pressure.

65 5. The combination of a wire expansion shield formed of a primary wire unit and a secondary wire unit, head members on the

primary unit one head member being lower than the other head member, and a head member on the secondary unit adapted to rest on the lower head member of the primary unit, and an expanding member having a head 70 adapted to engage with a head member on each of the primary and secondary units.

HENRY W. PLEISTER.
JOHN KARITZKY.
